(57) **CLAIM**

I claim the ornamental design for a bed, as shown and described.

DESCRIPTION

FIG. 1 is a perspective view of a bed.

FIG. 2 is a side view of the bed of FIG. 1.

FIG. 3 is a front view of the bed of FIG. 1.

FIG. 4 is a rear view of the bed of FIG. 1; and,

FIG. 5 is a top view of the bed of FIG. 1.

Portions of the bed shown in broken line form no part of the claimed design.
